UNITED STATES PATENT OFFICE.

FRANCIS O. WHEALON, OF ST. PAUL, MINNESOTA, ASSIGNOR TO
INTERNATIONAL RAILWAY DEVICE COMPANY, A CORPORA-
TION OF MINNESOTA.

LOCOMOTIVE.

SPECIFICATION forming part of Letters Patent No. 789,111, dated May 2, 1905.

Application filed March 3, 1904. Serial No. 196,271.

To all whom it may concern:

Be it known that I, FRANCIS O. WHEALON, a citizen of the United States of America, and a resident of St. Paul, in the county of Ramsey and State of Minnesota, have invented 5 certain new and useful Improvements in Locomotives, of which the following is a specification.

My invention relates to improvements in 10 locomotives, and has for its object to provide means for preventing the cylinders on locomotives from cooling when the engine is what I have chosen to term "drifting."

A further object is simplicity of construction, together with effectiveness in use.

With this invention I have shown my improvement connected with the mechanism described in my Patent No. 741,859, dated the 20th day of October, 1903.

20 My invention consists in making a direct communication between the ends of the cylinder, said communication being caused to open and close automatically as the live steam is turned into or checked from the cylinder.

25 This invention enables the engine to drift more freely, and avoids taking a cylinder full of cold air at each and every stroke of the piston by using the same air that is being pushed out of one end of the cylinder through 30 said communication and into the other end of the cylinder. This reduces condensation of the steam in the cylinder and affects greater saving of power.

Further, this invention conducts any steam 35 that leaks into the steam-chest, while the engine is at rest, to the top of the smoke-stack. Leaky steam has heretofore egressed through the suction-valve and has obstructed the view of the operators. This objection is overcome 40 with my invention. The effect of the piston moving in the cylinder when the engine is drifting does not increase the draft, and in consequence saves fuel and deterioration of the flues.

45 This invention thus contemplates a connection between the inlet-port passage-ways having an outlet into the variable-exhaust mechanism described in my patent above referred

to, and a relief or back-pressure valve controlling said outlet.

50 In the accompanying drawings, forming part of this specification, Figure 1 is a side view of a cylinder of a locomotive, showing my improved mechanism connected therewith. Fig. 2 is an enlarged end view of one of the 55 cylinders and a detail portion of a locomotive. Fig. 3 is an end elevation of a locomotive, showing the cylinders and the mutual relation of their exhausts and my improved mechanism; and Fig. 4 is a sectional side view of 60 Fig. 1, showing the steam inlet and outlet port passage-ways.

In the drawings let A represent one of the cylinders on a locomotive, B a detail portion of the locomotive, and C the ordinary exhaust 65 passage-way between the cylinder and the smoke-chamber D.

E is an auxiliary passage-way leading from the exhaust-outlet in the cylinder to a point outside of the smoke-chamber for the purpose of conducting the exhaust and all leaky steam, which obstructs the operator's view, to the top of the stack. A valve 2 is connected with the passage-way E and is adapted 70 to be operated by the rod 3, which may be 75 connected with an operating-handle located in the cab of the locomotive, as described in my patent above referred to, for the purpose of modifying the auxiliary exhaust passage-way E, leading outside of the smoke-chamber. 80 This valve 2 and its operating mechanism may or may not be connected to the reverse-lever, for it is obvious that an independent lever may be used or the valves operated directly by hand or otherwise.

85 Connected with the steam-chest G is a branch passage-way F, which has a suction-valve H of ordinary construction connected therewith, so that as the slide-valve 4 in the steam-chest reciprocates and live steam enters said chest 90 the suction-valve remains closed, and when the supply of live steam is cut off the action of the piston 5 in the cylinder opens said valve automatically and forces the hot air or steam from end to end in the cylinder, thus tending 95 to keep the cylinder hot and to prevent con-

densation of live steam when it is again admitted into the cylinder.

The steam-ports 6 and 7 (shown clearly in Fig. 4) receive and exhaust the steam in the ordinary manner during the operation of the engine. The passage-ways F and E, steam-chest G, main exhaust-port 8, and valve 4 communicate between the ports 6 and 7 and the ends of the cylinder when the engine is drifting, and the valve H relieves the back-pressure steam in the cylinder.

In operation when steam is turned into the cylinder the piston 5 and slide-valve in the steam-chest reciprocate in the ordinary manner, and the steam is free to exhaust through the main exhaust passage-way C. When it is desired to check the draft, the valve 2 is opened to decrease the amount of exhaust-steam passing through the passage-way C and to allow part of it to escape through the auxiliary passage-way E to the exterior of the smoke-chamber. To accelerate the draft, the valve 2 is partially or wholly closed.

It is obvious that the rod 3 can be connected to an operative part of the locomotive, such as the reversing-lever, and thus made to act automatically in connection with the operating mechanism, or that it can be connected to a simple lever, which is attached to the reversing-lever, and its ratio made to change by hand to operate the valve 2.

When the engine is at rest, the check-valve H is open, and any steam leaking through the throttle-valve and passing into the steam-chest and cylinder is free to escape through the auxiliary passage-way E to the top of the smoke-stack by opening the valve 2 and does not increase the draft in the smoke-chamber.

It is obvious that the mechanism above described may be modified and constructed in numerous ways without departing from the principles which I have applied and used on simple or compound engines, and I do not wish to confine myself to the specific construction specified. For instance, a single valve may be used in place of two valves on the variable-exhaust passage-way E and operated by any suitable mechanism desired without departing from the spirit of this invention.

Having described my invention, what I claim as new, and desire to protect by Letters Patent, is—

1. A locomotive having a steam-cylinder provided with an exhaust-port, which is connected with the smoke-chamber, a piston, a steam-chest, a passage-way leading from said exhaust-port to the open air and having a branch to said steam-chest, valve mechanism connected with said passage-way, means for operating said valve mechanism, and a check-valve in said branch.

2. In combination with a locomotive-cylinder, its piston and steam-chest, a passage-way connected with said steam-chest and the exhaust-port leading from said cylinder and hav-

ing a branch outlet, and a valve in said passage-way.

3. In combination with an engine-cylinder, its piston and steam-chest, a passage-way connecting said steam-chest with the exhaust-outlet leading from said cylinder and having an outlet, and an automatic valve in said passage-way.

4. In combination with a cylinder, steam-chest and valve, having live and exhaust steam connections, a communication between said live and exhaust steam connections having a branch outlet, and a valve in said communication adapted to open into the steam-chest when live steam is cut off and the piston is in motion and close when live steam enters said steam-chest.

5. In combination with the cylinder of a steam-engine, its piston, exhaust-opening and live-steam inlet, a valve for modifying said exhaust-opening, a passage-way connecting the exhaust-opening with said live-steam inlet, a valve in said passage-way to close the same when live steam is entering the cylinder and open it when the supply of live steam is checked, and an outlet leading from said passage-way at a point between said exhaust-opening and said last-described valve.

6. In combination with a locomotive, its steam-chest and exhaust passage-way from the cylinder to the smoke-chamber, of an auxiliary passage-way leading to a point outside of said smoke-chamber, for the exhaust-steam, a valve in said auxiliary passage-way, means for operating said valve, a connection between said steam-chest and said auxiliary passage-way, and an automatic valve in said connection to open the same when the supply of live steam to said chest is checked.

7. A device of the class set forth, consisting, in combination with a locomotive having a smoke-chamber, its cylinders and a main exhaust passage-way leading from the cylinders and projecting into said smoke-chamber, of an auxiliary passage-way connected with said main exhaust passage-way, having valve mechanism for modifying the size of the same, a connection between the auxiliary passage-way and the steam-chest in each of said cylinders, and an automatic valve in said connection.

8. In combination with a locomotive having a main passage-way forming an exhaust-outlet between the cylinders and the smoke-chamber, a branch passage-way from said main passage-way leading to the exterior of said smoke-chamber, means for modifying the size of said branch passage-way, a connection between the steam-inlets of said cylinders and said branch passage-way, and automatic valve mechanism in said connection.

9. A device of the class set forth, comprising a passage-way between the cylinders and smoke-chamber of a locomotive for the exhaust-steam, a branch passage-way from said

- first passage-way to the exterior of said smoke-chamber, valve mechanism for regulating the size of the outlet of said branch passage-way, lever mechanism for operating said valve mechanism, a connection between the branch passage-way and the live-steam inlets of said cylinders, and valve mechanism in said connection.
10. An engine-cylinder having an exhaust-port, a piston, a steam-chest, a passage-way leading from said exhaust-port to the open air, a valve in said passage-way, means for operating said valve, a branch from said passage-way connected with said steam-chest, and a valve in said branch.
11. An engine-cylinder having an exhaust-port, a piston, a steam-chest, a passage-way opening from said exhaust-port and having a branch connected with said steam-chest, and valve mechanism in said passage-way and its connection.
12. A locomotive having steam-cylinders, each provided with a piston, steam-chest and exhaust-port connected with the smoke-chamber, passage-ways between the exhaust-ports and steam-chests of said cylinders, valve mechanism connected with said passage-ways to close the same when live steam is entering said cylinders and open when the supply of live steam is checked, and a branch to said passage-ways leading from said smoke-chamber.
13. A locomotive having a steam-cylinder provided with a piston, steam inlet and outlet ports, a valve controlling said ports, draft mechanism in the locomotive, a passage-way

connecting the outlet-port with the outer air, a connection between the steam-inlet ports and said passage-way, and valve mechanism in said connection.

14. A locomotive having a steam-cylinder provided with inlet and exhaust ports, a valve to control said ports, a draft passage-way leading from the exhaust-port and having a branch opening into the outer air to form variable exhaust mechanism, a connection between said branch and inlet-ports, and valve mechanism in said connection.

15. A locomotive having draft mechanism, a steam-cylinder provided with live and exhaust steam ports, a piston, a steam-chest, a valve controlling said ports, a passage-way connecting the exhaust-port with the outer air, a connection between said live-steam ports and said passage-way, and valve mechanism in said passage-way and connection.

16. A locomotive having a steam-cylinder provided with live and exhaust steam ports, the latter connected with the smoke-chamber, a piston, a steam-chest, a passage-way leading from said exhaust-port to the outer air, a connection between said live-steam ports and passage-way, and a relief or back-pressure valve in said connection.

In testimony whereof I have signed my name to this specification in the presence of two subscribing witnesses.

FRANCIS O. WHEALON.
